UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

STITCH-FORMING MECHANISM FOR SEWING MACHINES.

1,405,855.

Specification of Letters Patent. Patented Feb. 7, 1922.

Application filed July 18, 1917. Serial No. 181,208.

To all whom it may concern:

Be it known that I, JAMES R. MOFFATT, a citizen of the United States, residing at Chicago, in the county of Cook, State of

5 Illinois, have invented certain new and useful Improvements in Stitch-Forming Mechanism for Sewing Machines, of which the following is a description, reference being had to the accompanying drawing and to

10 the figures of reference marked thereon.

The invention relates to new and useful improvements in stitch-forming mechanisms for sewing machines, and more particularly to the mechanism for laying a cross-thread 15 between and connecting needle threads on the upper surface of the fabric.

An object of the invention is to provide a stitch-forming mechanism of the above character having a thread-hook for engaging 20 the cross-thread and forming a loop therein, and with a stationary finger against which the cross-thread is drawn by the hook, which stationary finger is so constructed as to move the cross-thread rearwardly for 25 positioning the same between the needles.

A further object of the invention is to provide a movable thread-guide co-operating with said stationary finger for returning the thread along the finger to its initial position 30 for re-engagement by the hook.

These and other objects will in part be obvious and will in part be hereinafter more fully disclosed.

In the drawings,—

35 Figure 1 is a front view of a sewing machine embodying my improvements and having a part thereof broken away to show the looper;

Figure 2 is an enlarged front view of the 40 end of the sewing machine with the edging guide removed;

Figure 3 is an end view of the machine, showing the parts at the end of the overhanging arm, the overhanging arm being 45 omitted;

Figure 4 is a view partly in top plan and partly in section, the section being taken directly beneath the lower bearing of the overhanging arm;

50 Figure 5 is a perspective view showing the needles, the thread-hook, the thread finger and the thread-guides for the cross-thread, the hook being at the forward end of its stroke;

55 Figure 6 is a plan view showing the

thread-hook, the thread finger, the guides for the cross-thread with the hook at the forward end of its stroke; and also showing the fabric, the edging and the inter-chained cross-thread and needle-threads; 60

Figure 7 is a view similar to Figure 5, but showing a slightly modified form of stationary thread-finger;

Figure 8 is a plan view showing the thread-hook, the thread-finger and the fixed 65 thread-guides for the cross-thread;

Figure 9 is a view similar to Figure 5, but showing the hook at the rear end of its stroke and as about to engage the cross-thread; 70

Figure 10 is a diagrammatic view, showing the relation of the threads to the fabric and the edging.

The invention is embodied in a stitching mechanism consisting of a plurality of 75 needles which are arranged abreast and with which a single looper co-operates beneath the work support. Co-operating with these needles above the work support is a cross-thread-laying hook adapted to engage a 80 cross-thread and form a loop therein for one of the needles to enter.

Associated with the cross-thread-laying hook is a finger against which the cross-thread is drawn, and this finger is so shaped 85 that the pull of the hook on the cross-thread will cause the cross-thread to slide rearwardly on the finger and be positioned between the needles. Also associated with the finger and the cross-thread-laying hook is a 90 thread-guide movable up and down with the needle bar, through which the cross-thread extends, and this thread-guide on its downward movement serves to bring the cross-thread to its forward position on the thread-finger where it will be engaged by the hook as it next moves forward to form a loop.

Referring more in detail to the drawings, my improved stitch-forming mechanism is shown as applied to a sewing machine having 100 a work support 1, an overhanging arm 2 in which reciprocates a needle bar 3, carrying a pair of needles 4 and 5. Co-operating with the needles 4 and 5 beneath the work support is a threaded looper 6. Said looper is pivoted 105 at 7 and is oscillated by a link 8. This link 8 is pivoted at its other end to the needle lever extension 9 carried by the needle lever 10. The needle lever 10 is connected by a link 11 to the needle bar. 110

The needle lever is oscillated by the eccentric strap 12 which co-operates with the eccentric on the main shaft, and the main shaft is rotated by the usual belt wheel 13.

5 The material is held on the work support by a presser foot 14 carried by a presser bar 15 mounted in the overhanging arm. The needle 4 is provided with a needle-thread 4^a, while the needle 5 is provided with a needle-thread 5^a. These needle-threads pass through a suitable guide 16 at the upper end of the needle bar and also through guides 17 and 18 on the needle lever. Said threads between the guides 17 and 18 pass through a thread-guide 19. These thread-guides and the stitching mechanism described, are of the well known construction and further detail description thereof is not thought necessary. The needles pass down through the fabric 20 and the looper enters both thread-loops formed by the needles, and the looper-thread is thereby concatenated with both needle-thread loops.

The needle-threads are joined on the upper 25 face of the fabric by a cross-thread 20. This cross-thread is led from a tension 21 through spaced guides 22, 22; and thence through a fixed thread-guide 23 formed in an arm 24 secured to a bracket 25 attached to the overhanging arm of the machine. An arm 22^a carried by the needle bar engages the cross-thread between the guides 22, 22 for pulling off the cross-thread.

Mounted on the needle bar 3 is an arm 26 having a thread-eye 27. The cross-thread passes through this thread-eye. The cross-thread is formed into loops by a thread-hook 28. This thread-hook is formed with a notched end 29 and with a shank 30, which 35 extends vertically through a sleeve 31 carried by a lever or thread-hook carrier 32. The shank 30 is adjustably held in the sleeve by means of screws 33, 33. The lever 32 extends to the rear of the overhanging arm, and is 40 pivotally supported by the bracket 25. Said bracket has spaced ears carrying a vertical shaft 34, to which the lever 32 is secured.

The lever 32 is provided with a ball stud 35 and a link 36 is pivotally attached to this 50 ball stud. The link 36 at its other end is pivotally connected at 39 to a bracket 40 carried at the lower end of the needle lever extension 9. As the needle lever extension oscillates, the lever 32 will be oscillated, and this will 55 move the thread-hook back and forth across the line of feed, or across a vertical plane passing centrally between the needles. The path of the thread-hook is entirely in front of the needles.

60 Associated with the thread-hook is a thread-finger 41. This thread-finger 41 is carried by an arm 42. The arms 42 and 24 are preferably formed from one piece of metal and these arms are secured to the 65 bracket 25 by screws 43. The slots through

which the screws extend are elongated vertically, so the arm 42 may be raised and lowered slightly.

The thread-finger 41, as shown in the drawings, is provided with a slot 43. The 70 wall 44 of this slot is, however, the only active surface against which the thread is moved. As clearly shown in the drawings, this surface is shown as consisting of a concave curved surface, which leads into a 75 convex curved surface, the convex curved surface forming the curved shoulder 45.

When the needles are clear down, as indicated in Figure 9 of the drawings, the thread-hook is at the extreme rear end of 80 its stroke. The thread-guide 27 for the cross-thread is at the lower end of its stroke and is so disposed relative to the finger 41 as to draw the cross-thread forward on the finger to a point adjacent the forward end 85 of the slot. When the cross-thread is thus positioned, as the hook moves forward, it engages the cross-thread. That is to say, the notch in the thread-hook moves underneath the finger at the forward end of the 90 curved slot. After the hook has engaged the cross-thread, it forms the cross-thread into a loop in the well known way, which loop will be entered by the needle farthest from the thread-finger. It is also desirable 95 that the cross-thread should pass between the needles. As the hook moves forward, it pulls the cross-thread against this thread-finger and the guide 27 moving upwardly away from the finger, permits the pull on 100 the thread to draw the thread rearwardly along the finger.

Inasmuch as the finger is concave at the forward end thereof, the thread will be given up quickly and easily to the hook. 105 Just as the thread is reaching the rear end of its movement along the finger, it slides along the convex curved shoulder 45 and this takes any slack out of the thread, so it will be held taut by the hook until 110 needles are past the thread.

When the cross-thread reaches this position, as clearly shown in Figure 5, the needles will pass down, one on each side of the thread between the notch in the hook 115 and the thread-finger, and the left hand needle or needle 4 will enter the thread-loop formed in the cross-thread. When the thread-hook returns, the loop is dropped, and the movable thread-eye on the needle 120 bar will draw the cross-thread again to the forward end of the slot.

In Figure 7 of the drawings I have shown a slightly modified form of thread-finger 41. In this form of thread-finger there is no 125 slot, but the surface 44 is shaped substantially as above described and the cross-thread slides along this surface. The thread-hook may be adjusted vertically and also the thread-finger may be adjusted 130

vertically, to bring these parts into proper co-operative position relative to the needles.

In the drawings I have shown my improved stitch-forming mechanism as used 5 for stitching a lace edging indicated at E to a fabric indicated at F. The edging is led through a suitable guiding device 46; thence through a guiding device 47; and thence around a guiding roller 48, carried 10 by the presser foot. The edging is directed so as to slightly overlap the edges of the fabric. The needles 4 and 5 both penetrate the fabric and the needle 5 passes through the edging. The needle-threads are connected below by the looper thread, and are connected above by the cross-thread, and the cross-thread thus firmly secures and covers the edge portion of the edging where it is joined to the fabric.

20 From the above description, it will be apparent that I have provided a cross-thread-laying mechanism in which the cross-thread is positively handled by a minimum number of movable parts, and, therefore, 25 there is little or no wear on the cross-thread and it will be laid with certainty relative to the needles.

It is obvious that minor changes in the details of the construction may be made, 30 without departing from the spirit of the invention as set forth in the appended claims.

Having thus described my invention, what I claim as new and desire to secure by Letters Patent, is:

1. The combination with a plurality of needles and complemental stitch-forming mechanism, of a thread hook for forming a loop in a cross thread for certain of said 40 needles to enter, means against which the cross thread is drawn by the hook, said means being shaped so that, as the cross thread is forced against the same by the hook, said cross thread will move rearwardly while in engagement with said means and position one strand of the loop between the needles.

2. The combination with a plurality of needles and complemental stitch-forming mechanism, of a thread hook for forming a loop in a cross thread for certain of said 50 needles to enter, a thread finger against which the cross thread is drawn by the hook, said finger being shaped so that, as the cross thread is forced against said thread finger by the hook, said cross thread will move rearwardly while in engagement with said thread finger and position one strand of the cross thread between the needles.

3. In a cross thread laying mechanism, the 60 combination with a plurality of needles and complemental stitch forming mechanism, of a feeding mechanism, a reciprocatory thread hook for forming loops in a cross thread for one of said needles to enter, means for operating said hook, a guide for the cross thread

disposed in a position above the path of movement of the free end of the hook and operating to position the thread in front of the hook so that said hook will engage the thread with certainty, and means against 70 which one strand of the loop is carried by the forward movement of said hook whereby said strand will be positioned between the needles, and feeding mechanism operating to rearwardly move the other strand of the loop 75 whereby the needle farthest removed from said thread guide will enter the loop with certainty.

4. The combination with a plurality of needles and complemental stitch-forming 80 mechanism, of a thread-hook for forming a loop in a cross-thread for one of said needles to enter, and a fixed thread-finger against which the cross-thread is drawn, said finger having a curved surface disposed relative to 85 the movement of the hook, so that the pull of the hook will cause the thread to move backward on the finger and be properly positioned relative to the needles.

5. The combination with a plurality of 90 needles and complemental stitch-forming mechanism, of a thread-hook for forming a loop in a cross-thread for one of the needles to enter, a vertically movable guide for the cross-thread, a stationary finger against 95 which the cross-thread is drawn by the hook, said finger being shaped so as to move the thread rearwardly to properly position the same relative to the needles as the hook pulls out the thread, and said thread-guide being 100 so positioned as to return the cross-thread to the forward end of the finger for engagement by the hook on its next forward movement.

6. The combination with a plurality of needles and complemental stitch-forming 105 mechanism, of a thread-hook for forming a loop in a cross-thread for one of said needles to enter, a fixed thread-finger having a curved face against which the cross-thread is drawn by the hook, said curved face operating to move the thread rearwardly as the hook pulls on the thread, the forward portion of the curved face against which the thread is pulled by the hook being concave and the rearward portion against which the 110 thread is drawn being convex, said convex surface co-operating with the hook to pull the thread taut.

7. The combination with a plurality of needles and complemental stitch-forming 120 mechanism, of a thread-hook for forming a loop in a cross-thread for one of said needles to enter, a fixed thread-finger having a curved face against which the cross-thread is drawn by the hook, said curved face operating to move the thread rearwardly as the hook pulls on the thread, the forward portion of the curved face against which the thread is pulled by the hook being concave and the rearward portion against which the thread 125

is drawn being convex, said convex surface co-operating with the hook to pull the thread taut, and a vertically movable thread-guide for the cross-thread, said vertically movable thread-guide being positioned so as to move the thread forward on said finger when released by the hook into position to be engaged by the hook on its next forward movement.

8. The combination with a needle bar, a plurality of needles and complemental stitch-forming mechanism, of a thread-hook for forming a loop in a cross-thread for one of the needles to enter, a stationary finger against which the cross-thread is drawn by the hook, said finger being shaped so as to move the cross-thread rearwardly as the thread is pulled thereagainst by the hook, a thread-guide carried by the needle-bar for said cross-thread, said thread-guide being so positioned that in its vertical movements

said thread-guide will move the thread forward on the finger when released by the hook and position the same for engagement by the hook on its next forward movement.

9. The combination of a plurality of needles, a cross-thread-laying hook, a fixed thread-finger co-operating with said cross-thread-laying hook, a lever for supporting said hook, said hook being attached to said lever, whereby the same may be adjusted vertically, and means for supporting said fixed thread-finger whereby it may be vertically adjusted.

In testimony whereof, I affix my signature in the presence of two witnesses.

JAMES R. MOFFATT.
